Specification for Design.

Patented Oct. 30, 1917.

Application filed September 17, 1917. Serial No. 191,874. Term of patent 14 years.

To all whom it may concern:

Be it known that I, CYRUS F. BLANKE, a citizen of the United States, residing at St. Louis, State of Missouri, have invented a new, original, and ornamental Design for a Suitcase, of which the following is a specification.

In the drawings—

Figure 1 is a perspective view of a suitcase embodying my new design.

Fig. 2 is a side elevation of the same.

Fig. 3 is an end elevation.

Fig. 4 is a bottom plan view.

I claim:

The ornamental design for a suitcase, substantially as shown.

In testimony that I claim the foregoing as my own, I have hereto affixed my signature in the presence of two witnesses.

CYRUS F. BLANKE.

Witnesses:

E. ROWSE THOMPSON,

H. D. BILLINGS.
